METHOD FOR RECOVERING HYDROXY-3- ETIOCHOLENIC ACID AND ITS ESTERS

Rupert Oppenauer, Amsterdam, and Carel Christof Bolt, Oss, Netherlands, assignors to Roche-Organon Inc., Nutley, N. J., a corporation of New Jersey

No Drawing. Application February 6, 1940, Serial No. 317,608. In the Netherlands March 16, 1939

10 Claims. (Cl. 260—397.1)

This invention relates to a process for recovering hydroxy-3-*etiochenolic acid* and its esters from mixtures with homologous acids.

The hydroxy-3-*etiochenolic acid*, an important intermediate product in the preparation of substances showing a hormone action, has been prepared for the first time by decomposition of hydroxy-3-*bisnorchenolic acid* (of copending application by Rupert Oppenauer, Ser. No. 195,158, filed March 10, 1938). This starting material, however, is rather expensive. In the search for another starting material it appeared that the hydroxy-3-*etiochenolic acid* also occurs in the acid reaction products formed by the oxidation of sterols, e. g., cholesterol, with chromic acid, though the British specification No. 453,773 does not mention the hydroxy-3-*etiochenolic acid* as a component of the homologous acids occurring in the acid oxidation products.

It now has been found that it is possible to recover the desired *etio-acid* from the mixture so obtained in a surprisingly simple manner by subjecting the esters of these acids, preferably the methyl esters, to a direct fractional crystallisation. If desired, a preliminary purification may be carried out utilising the fact that some of the acids contained in the crude mixture among which is found the hydroxy-3-*etiochenolic acid*, form a difficultly soluble sodium salt. For carrying out the present method, however, this preliminary purification is not essential.

We have further found that the esters of hydroxy-3-*etiochenolic acid*, and particularly the methyl esters, have a substantially lower solubility in organic solvents than the esters of the other acids. This difference in solubility appears very distinctly in solvents consisting entirely or partly of hydrocarbons. Particularly suitable are mixtures of aliphatic and aromatic hydrocarbons. As aliphatic hydrocarbons the pure hydrocarbons, such as pentane, hexane and the like, may be used, but the cheaper petroleum ether consisting of a mixture of such hydrocarbons is also suitable. From the aromatic hydrocarbons benzene and toluene may be mentioned as an example.

The ester fraction obtained by the first crystallisation is already rather pure hydroxy-3-*etiochenolic acid* ester; by recrystallising a number of times from the same solvent the substance is easily obtained in pure condition.

The esters may be prepared in the usual manner, e. g., by boiling with the desired alcohol in presence of sulphuric acid, aromatic sulphonic acids such as toluene sulphonic acid, and the

like. The neutral esters are then freed from acids remained unesterified and/or acid esters by means of alkali, after which they are subjected to the crystallisation as above described.

- 5 The esters used in the examples are obtained by the oxidation of cholesterol; the method may, however, be carried out with equally good results with the acids obtained by the oxidation of other sterols.
- 10 The pure esters obtained may subsequently be converted into the corresponding acids by saponification.

Example 1.—The acids obtained from the insoluble sodium salts were esterified with methanol under the influence of sulphuric acid. The esters obtained in this manner were freed from the acid components, e. g., by extraction with carbon tetrachloride from an aqueous alkaline medium, the acid components remaining in the

20 aqueous medium.

620 g. of the methyl esters obtained in that manner were dissolved in 1200 cm.³ of benzene after which 600 cm.³ of petroleum ether (B. P. 40–60° C.) were added. The mixture was allowed 25 to stand some days at room temperature, whereupon the precipitate formed was filtered off with suction and recrystallised a number of times from a mixture consisting of 2 parts of benzene and 1 part of petroleum ether. In this manner 17 g. 30 of hydroxy-3-*etiochenolic acid* methyl ester having a melting point of 178–180° C. was obtained which appeared to be identical with the methyl ester of hydroxy-3-*etiochenolic acid* obtained by decomposition of hydroxy-3-*bisnorchenolic acid*.

Example 2.—5 g. of still impure hydroxy-3-*etiochenolic acid* methyl ester were dissolved in 150 cm.³ of toluene and 100 cm.³ of petroleum ether. After keeping 2 days in the refrigerator 4 g. of pure ester having a melting point of 178–40 180° C. could be recovered.

Example 3.—750 g. of crude methyl esters were dissolved in a mixture of 700 cm.³ of toluene and 250 cm.³ of petroleum ether. After some days the precipitate which had formed, and which 45 weighed 41.7 g., was recovered. From this precipitate 30 g. of pure hydroxy-3-*etiochenolic acid* methyl ester having a melting point of 178–180° C. were obtained by recrystallising twice from a mixture of toluene and petroleum ether.

Example 4.—620 g. of crude methyl esters were dissolved in a mixture of 1000 cm.³ of benzene and 350 cm.³ of petroleum ether (B. P. 40–60° C.). After being kept 3 days at room temperature the precipitate weighing 80 g. was recovered by filtration with suction and recrystallised twice from 55

a mixture of benzene and petroleum ether having the same composition, whereby 40 g. of pure methyl ester having a melting point of 178-180° C. was obtained.

Various changes may be made in the details disclosed in the foregoing specification without departing from the invention or sacrificing the advantages thereof.

We claim:

1. A method for recovering hydroxy-3-etiocolenic acid and its esters from mixtures with homologous acids, comprising esterification of the mixture of acids, fractional crystallisation from a solvent containing essentially at least one hydrocarbon and recovery of the hydroxy-3-etiocolenic acid ester from the first crystal fractions.

2. A method for recovering hydroxy-3-etiocolenic acid and its esters from mixtures with homologous acids, comprising conversion of the mixture of acids into the methyl esters, fractional crystallisation from a solvent containing essentially at least one hydrocarbon and recovery of the hydroxy-3-etiocolenic acid methyl ester from the first crystal fractions.

3. A method for recovering hydroxy-3-etiocolenic acid and its esters from mixtures with homologous acids, comprising esterification of the mixture of acids, fractional crystallisation from a solvent containing essentially a mixture of hydrocarbons and recovery of the hydroxy-3-etiocolenic acid ester from the first crystal fractions.

4. A method for recovering hydroxy-3-etiocolenic acid and its esters from mixtures with homologous acids, comprising esterification of the mixture of acids, fractional crystallisation from a solvent consisting of a mixture of benzene and a low boiling petroleum ether and recovery of the hydroxy-3-etiocolenic acid ester from the first crystal fractions.

5. A method for recovering hydroxy-3-etiocolenic acid and its esters from mixtures with homologous acids, comprising conversion of the mixture of acids into the methyl esters, fractional

crystallisation from a solvent consisting of a mixture of benzene and a low boiling petroleum ether and recovery of the hydroxy-3-etiocolenic acid methyl ester from the first crystal fractions.

6. Method of purifying esters of hydroxy-3-etiocolenic acid that comprises fractionally crystallizing same from a hydrocarbon solvent.

7. A method for obtaining hydroxy-3-etiocolenic acid and its esters comprising the steps of oxidation of sterols to obtain a resultant mixture of acids, esterification of said mixture of acids, fractional crystallization from a solvent containing essentially at least one hydrocarbon, and recovery of the hydroxy-3-etiocolenic acid ester from the first crystal fractions.

8. A method for obtaining hydroxy-3-etiocolenic acid and its esters comprising the steps of oxidation of sterols to obtain a resultant mixture of acids, conversion of said mixture of acids into the methyl esters, fractional crystallization from a solvent containing essentially at least one hydrocarbon, and recovery of the hydroxy-3-etiocolenic acid methyl ester from the first crystal fractions.

9. A method for obtaining hydroxy-3-etiocolenic acid and its esters comprising the steps of oxidation of sterols to obtain a resultant mixture of acids, esterification of said mixture of acids, fractional crystallization from a solvent consisting of a mixture of benzene and a low boiling petroleum ether, and recovery of the hydroxy-3-etiocolenic acid ester from the first crystal fractions.

10. A method for obtaining hydroxy-3-etiocolenic acid and its esters comprising the steps of oxidation of sterols to obtain a resultant mixture of acids, conversion of said mixture of acids into the methyl esters, fractional crystallization from a solvent consisting of a mixture of benzene and a low boiling petroleum ether, and recovery of the hydroxy-3-etiocolenic acid methyl ester from the first crystal fractions.
